UNITED STATES PATENT OFFICE.

HERMANN J. TENNEY, OF NEW YORK, N. Y., ASSIGNOR TO THE TENNEY COMPANY, OF NEW YORK.

DESIGN FOR A BOX.

SPECIFICATION forming part of Design No. 21,168, dated November 10, 1891.

Application filed April 28, 1891. Serial No. 390,836. Term of patent 3½ years.

To all whom it may concern:

Be it known that I, HERMANN J. TENNEY, a citizen of the United States, residing in the city, county, and State of New York, have invented and produced a new and original Design for Ornamental Covers for Bonbon-Receiptacles and the Like, of which the following is a specification, reference being had to the accompanying drawings, forming a part

thereof.

Figure 1 represents a perspective view of my design, and Fig. 2 a plan view of the same.

My design consists of the flap-like pieces a b c d , e f g h , i j k l , and m n o p , bearing the

raised or embossed figures $a s c r$, $e t g u$, $i v$ 15
 $k w$, and $m x o y$, somewhat resembling spear-points and forming, when taken together, a figure resembling a star.

What I claim, and desire to secure by Letters Patent, is—

A design for bonbon-boxes and the like, consisting of the design, substantially as shown.

HERMANN J. TENNEY.
